UNITED STATES PATENT OFFICE.

STEPHEN USTICK, OF PHILADELPHIA, PENNSYLVANIA.

IMPROVEMENT IN THE MODES OF LUBRICATING JOURNALS.

Specification forming part of Letters Patent No. 119,288, dated September 26, 1871; antedated September 15, 1871.

To all whom it may concern:

Be it known that I, STEPHEN USTICK, of the city of Philadelphia and State of Pennsylvania, have invented an improvement in lubricating the journals of shafts or a continuous line of shafts, of which the following is a specification:

The nature of my invention consists in the connection of a tube or a line of tubes with the oil-chamber in the pillow-blocks or lower bearings of the journals of a shaft or a line of shafts, in such a manner as to have a continuous communication between the said chambers, so that in the feeding of the oil to one of them the whole are supplied at the same time, as hereinafter described.

To enable others skilled in the art to which my invention appertains to make a practical application of the same, I will now give a full description thereof.

In the accompanying drawing, which makes a part of this specification, Figure 1 is a plan view of a shaft, A, the bearings B, oil-reservoir F, and tubes E. Fig. 2 is a side elevation of the same.

Like letters in all the figures indicate the same parts.

A is a horizontal shaft. B B are pillow-blocks of the same. C C are the journal-caps. D D are the oil-chambers in the pillow-blocks B B. E E are tubes in connection with said oil-chambers. F is an oil-reservoir for supplying the oil to the chambers D.

The operation is as follows: The oil from the reservoir F passes into the chambers D, in communication therewith, by means of the vertical tube G, and flows through the tubes E into all the chambers D of the pillow-blocks connected with the shaft A or line of shafts. The oil passes from the chambers D to the respective journals a through small openings leading thereto from the chambers or through fibrous materials in larger openings. The reservoir F may be dispensed with by making one or more of the chambers D of sufficient capacity to hold the requisite supply of oil. When a shaft is provided with a pulley or pulleys the tube or tubes E should be bent to turn around the same, as illustrated by dotted lines in Fig. 2.

What I claim as my invention, and desire to secure by Letters Patent, is—

The combination and arrangement of the oil-tubes E with the chambers D of the pillow-blocks B, substantially in the manner and for the purpose above set forth.

In testimony that the above is my invention I have hereunto set my hand and affixed my seal this 19th day of November, 1870.

STEPHEN USTICK. [L. S.]
